PACKAGE-HEADING MACHINE.

1,123,292.

Specification of Letters Patent.

Patented Jan. 5, 1915.

Application filed November 25, 1910. Serial No. 594,072.

To all whom it may concern:

Be it known that I, HENRY C. HERR, a citizen of the United States of America, residing at Detroit, in the county of Wayne and State of Michigan, have invented certain new and useful Improvements in Package-Heading Machines, of which the following is a specification, reference being had therein to the accompanying drawings.

10 The invention relates to package heading machines and consists in the construction as hereinafter set forth.

In the drawings,—Figure 1 is an elevation of the machine partly in section; Fig. 15 2 is an elevation viewed at right angles to Fig. 1; Fig. 3 is a vertical central section through the nailing mechanism; Fig. 4 is a sectional plan view thereof; Fig. 5 is a cross section through a portion of the as-20 sorting mechanism; and Fig. 6 is a horizontal section showing the operation of the flange rolling mechanism. Fig. 7 is a partial vertical central section of the flange rolling mechanism pressing the rim into place, 25 the figure also showing the action of the anti-friction rolls.

The improved machine is capable of being used for the heading of packages of various constructions but as illustrated and specifically described, it is particularly designed for use in the heading of packages having cylindrical bodies formed of spiral wrappings of paper or similar material. The heads are formed of wood and are provided with the usual croze of barrel construction, but as the body is not provided with a groove the head is engaged with a chine-hoop formed of metal. This hoop has a V-shaped groove to fit the croze of the 35 head and is of a size corresponding to the internal diameter of the body so as to be capable of entering the end thereof. The hoop is also preferably provided with a return bent flange which passes around the 40 end of the cylindrical body and over the outer edge thereof, forming a metallic reinforcement.

The operations performed by the machine are first, the pressing of the head and chine-hoop into engagement with the end of the cylindrical body; second, the rolling down of the outer flange of the chine-hoop which is originally of the flaring form to permit the entrance of the end of the paper body;

third, the automatic nailing of the head, 55 the nails being distributed around the body and arranged to pass through the same, the chine-hoop, and into the head in a radial direction. These operations are performed by a mechanism, the detail construction of 60 which is as follows: The frame of the machine is preferably formed of a bed A, standards B rising therefrom, and an annular top frame C mounted at the upper ends of said standards. Centrally within 65 this frame is a vertical movable plunger or work supporting table D which is reciprocated by suitable mechanism such as a crank E and pitman F. The plunger is guided in slide-ways G on the standard, 70 and the crank is mounted on a shaft H driven at slow speed through the medium of the step-down gear train I from a drive shaft J, while the clutch K and trip pedal L control the cycle of movement. The 75 arrangement is such that during each cycle the plunger or work table D is raised and lowered again by one complete revolution of the crank.

The body of the package to be headed is 80 placed upon the work table D, the lower end engaging the circular guide D' which properly centers the work. The upper end of the body upon which the head and chine-hoop is placed, is in registration with an 85 annular guide M and an annular abutment N, these parts operating during the rise of the plunger to force the head and chine-hoop into full engagement with the cylindrical body. To provide for slight inequality in size, the plunger D is provided with a yielding top plate D² resiliently supported on springs D³. This yielding connection is also employed for another important function, that is to provide a suitable interval 90 of delay between the completion of engagement of the head with the body and the lowering of the work in which the flange closing and nailing operations may be performed. Thus while the movement of the 95 crank and plunger is continuous the movement imparted to the work is intermittent.

Flange-closing Mechanism.—As has been already described, the chine-hoop O is provided with a return bent flange O' for fitting over the end of the paper body and this flange is originally of a flaring form to receive the end of the body and to guide

it into full engagement with the hoop. The flared flange is then closed down into close engagement with the body by the operation of presser rolls. The rolls P are distributed about the package body and are carried by a revoluble annular member which also constitutes an element in the nailing mechanism, to be hereinafter described. The member P' is supported upon the annular member C and is provided with peripheral gear teeth P² which are in mesh with the pinion P³ on the vertical shaft P⁴ intermittently driven by a bevel pinion P⁵ engaging an interrupted bevel gear wheel P⁶ on one of the members of the gear train I. This mechanism will impart an intermittent rotary movement to the annular member P' and the timing is such that the member P' begins its rotation upon the completion of the full engagement of the head with the body and continues to rotate during the interval of delay caused by the compression and expansion of the springs D². The member P' then remains stationary during the remainder of the cycle and while the work on the plunger is being lowered.

During the intermittent rotation of the member P' the rolls P travel about the flange of the chine-hoop and the distance traveled is sufficient to cause the rolling down of all portions of the flange. As preferably constructed and as shown, the annular member P' travels during each movement, one third of a revolution and as there are six rolls equally spaced the operations performed thereby are equivalent to two complete revolutions of a single roll. In their normal positions the rolls P are sufficiently withdrawn from the chine-hoop to provide an unobstructed path for the latter as it is forced upward against the abutment N. During the initial movement of the member P', the rolls are brought into contact with the periphery of the chine-hoop and are held there during the continued movement, this being accomplished by the following construction: Q are rockable members pivotally attached at Q' to the member P' and extending inward therefrom. The rolls P are journaled at the front ends of the members Q and the latter are normally arranged at a slight angle to the radius of the member P' being yieldably held in this position by springs Q² which draw them against adjustable stops Q³. In this position the rolls are withdrawn from contact with the chine-hoop as has been already stated, but adjacent to the rolls are arranged yieldable stops Q⁴ which project from the stationary member N' on which the abutment N is formed. The stops Q⁴ project outward from the member N' into the path of movement of the rolls P during the rotary movement of

the member P' and form a sufficient obstacle to temporarily arrest said roll and cause the arm Q to swing upon its pivot. This movement will continue until the arm Q bears against an adjustable stop Q⁵ on the opposite side thereof, after which the arm Q and roll P are compelled to rotate with the member P' riding from the stop Q⁴ by pressing the latter inward against the tension of a spring Q⁶. The swinging movement of the arm Q will carry the roll P inward into contact with the chine-hoop which is pressed against the cylindrical body of the package and during the continued operation is rolled in firm contact therewith. At the completion of the movement the springs Q⁶ will draw the arms Q again against the stop Q⁵ withdrawing the rolls P from contact with the hopper. The nails are preferably automatically fed from a hopper R and deposited point foremost into conduits T².

Nail driving mechanism.—The nails in falling through the conduits will acquire considerable velocity, and to prevent recoil when reaching the end of their course, a special construction is provided. This consists of a pocketed member W preferably mounted upon the revoluble member P' and having an inclined deflecting face W'. This pocket is registered with the corresponding conduit T² at the time of release by movement of the gate T³, and the nail traveling down the conduit, head foremost, will strike against the inclined shoulder W' and will be deflected downward. The pocket W is so fashioned that the head of the nail is permitted to pass downward through a slot W² at the outer end of the pocket, while the body of the nail passes through a slot of restricted width W³. This forms a shoulder W⁴ for engaging with the head of the nail and any recoil occasioned by the striking of the head against the outer end of the pocket will be prevented by the shoulder W⁴ which prevents inward movement of the nail but permits it to drop downward through the slots W² and W³. Beneath the pocket W in its position of rest, is a radial slot X in the member C, and alining with this slot is a nail driver X' which has an anti-friction roll X² engaging a cam slot X³ in the under face of the rotary member P'. The slot X³ is of a form to hold the driver X' at the outward end of its movement during a part of the revolution of the member P' and to impart an inward radial movement to said driver during another portion of the rotary movement of the member P'. Every alternate driver engages a similar portion of the cam slot X³, while the intermediate drivers engage a different portion of said slot, the arrangement being one to affect the simultaneous movement of one half of the drivers and alternately the simultaneous movement

of the other half. This will divide up the work of driving the nails and decrease the power required for the machine.

The rotary member P is preferably completely housed in a cap member P' which is secured to the annular member C and has dependent therefrom a flange N' on which the abutment M is formed. This flange N' also forms a journal for the rotary member P which is provided with anti-friction rolls N⁴ engaging said flange.

The construction being as described in operation, the workman first places the package body upon the table or plunger D centering it by engagement with the circular guide D'. At the same time a head with the chine-hoop in engagement therewith is placed at the top of the body with the lower end of the hoop just entered into engagement. Motion is then imparted to the machine by actuating the tripping pedal L which throws in the clutch K and communicates motion from the shaft J through the gear train I to the crank E, and through the abutment F to the plunger D. The plunger is thus raised, carrying up the package which is guided by the annular member M into engagement with the abutment N. Here further movement of the head and chine-hoop is prevented but the body continues to be forced upward until in full engagement with the head. This occurs before the crank has reached the upper limit of its movement and thus the plunger continues to rise but is permitted to do so without injury to the package by the compression of the springs D².

Upon the completion of the engagement of the head with the cylindrical body the interrupted gear P⁶ enters into mesh with the pinion P⁵, imparting rotary motion to the shaft P⁴ and thereby driving all of the mechanism at the upper end of the machine. This will instantaneously start the members P' in rotation causing the engagement of the rolls P with the stops Q⁴ and in the further movement of the member P' rocking the arms Q until arrested by the stops Q⁵. This presses said rolls inward against the flange of the chine-hoop and during the further movement of the member P' said flange will be rolled down against the cylindrical body. During the operation just described the rotation of the annular member P' will actuate the nail drivers X', one half of the number being first moved and at the completion of their movement the other half are operated. The nails for this operation have previously been deposited in the radial slots X and are in the path of movement of the drivers which force them inward, the point first penetrating the body and then the chine-hoop and the head. The V-shaped portion of the chine-hoop forms a guide for directing the point of the nail to the apex,

thus insuring that it will be properly directly in entering the wood of the head.

What I claim as my invention is:

1. In a package heading machine, the combination with means for forcing a flanged head into engagement with the body of a package, of associated means for rolling the flange about the periphery of the package body, and means for driving a series of nails radially inward through said body and into the head.

2. In a package heading machine, the combination with means for pressing a flanged head into the end of the package, of a member revoluble about the headed end of said package, flanged rolling means carried by said revoluble member, and means actuated by said revoluble member for driving nails radially inward through said body and into said head.

3. In a package heading machine, the combination with means for pressing a flanged head into engagement with the body of the package, of means for rolling the flange of the head over the end of the body, means for depositing a series of nails in spaced radial arrangement about said body, and means for driving said nails through said body and into said head.

4. The combination with a seat or abutment for receiving the headed end of a package, of an annular member surrounding said seat and having a series of radially arranged nail guide channels therein, a rotary member above said annular member, nail drivers alined with said channels and actuated by said rotary member, and flanged rolling means carried by said rotary member and operating upon said headed package.

5. The combination with a seat for a headed package, of a rotary annular member surrounding said seat, a stationary annular member adjacent to said rotary annular member, radially arranged nail driving means carried by said stationary annular member and operated by said rotary annular member, and flanged rolling means also carried by said rotary annular member and operating upon said headed package while in engagement with its seat.

6. The combination with a seat, of means for pressing a package against said seat to engage the head with the body of said package, adjacent stationary and rotary annular members surrounding said seat and package, radially arranged nail driving means on said stationary annular member operated by said rotary annular member, flanged rolling means carried by said rotary annular member, and timed mechanism for first pressing said package to its seat and then rotating said rotary annular member.

7. The combination of an annular seat or abutment, means for moving a package

- thereagainst to press the head into engagement with the body thereof, a rotary annular member surrounding and journaled upon said seat, a roll carried by said rotary member normally retracted from said seat to be out of the path of said headed package, and means operating upon the initial movement of said rotary member for pressing said roll radially inward to contact the same with the package on said seat.
8. The combination with a seat for engaging the head of the package to press the same into the body thereof, of nail driving mechanism surrounding said package while in engagement with said seat, a rotary member for operating said nail driving mechanism, a roll carried by said rotary member normally retracted from said seat to be out of the path of said headed package when engaged with its seat, and means operating upon the initial movement of said rotary member for pressing said roll radially inward into contact with the headed package on said seat.
9. The combination with a seat for pressing the head of a package into engagement with the body thereof, of nail driving mechanism surrounding said package while engaged with its seat, a rotary member for actuating said nail driving mechanism, a roll carried by said rotary member nor-

mally withdrawn out of the path of the package during engagement with said seat, a rock arm upon which said roll is mounted, and a yieldable stop for engaging said roll in the initial movement of said rotary member to cause the rocking of said arm and the carrying of the roll into engagement with the work.

10. In a package heading machine, the combination with means for engaging a flanged head with the body of a package, of means for pressing said flange down about the periphery of the package body, and means for driving a series of securing means radially inward through said body and into the head.

11. In a package heading machine, the combination with means for engaging a flanged head with the body of a package, of means for pressing said flange down about the periphery of the package body, and means for driving a series of securing means radially inward through said body and into the head, and mechanism for automatically operating all of said means.

In testimony whereof I affix my signature in presence of two witnesses.

HENRY C. HERR.
